UNITED STATES PATENT OFFICE.

ALVIE C. CRIMMEL, OF HARTFORD CITY, INDIANA.

MUFFLE LEER.

Application filed May 11, 1923. Serial No. 638,268.

To all whom it may concern:

Be it known that I, ALVIE C. CRIMMEL, a citizen of the United States, residing at Hartford City, in the county of Blackford, 5 State of Indiana, have invented a new and useful Muffle Leer, of which the following is a specification.

My invention relates to a novel construction of a muffle leer wherein a plurality of 10 independent removable muffles or muffle units are employed which are so collocated that in case of an explosion or the necessity arising for the removal of any one unit, this can be readily accomplished and a new 15 muffle or unit substituted without disturbing the other muffle units or necessitating the closing down of the leer for repairs which ordinarily requires a considerable period of time.

My invention further consists of a novel 20 construction of a series of independent removable muffle units arranged substantially in parallelism and in proximity to each other, each being provided with openings 25 at or near their opposite ends and supported upon the walls of the leer in such a way that neither the products of combustion nor the flame come in direct contact with the ware in the annealing chamber 30 which is annealed by the action of radiant heat radiated upon the ware from the muffle units and their adjuncts as hereafter described, the leer being fired by any desired type of fuel, as gas, oil, or producer gas.

It further consists of a novel construction 35 of a removable muffle unit comprising a rectangular or other box shaped casing of metal or other material which is closed on all sides and provided with openings 40 near its ends which are adapted to serve as inlet or outlet openings, as may be desired.

It further consists of the novel combination 45 of a leer provided with inlet and outlet flues coacting with the inlet and outlet openings of removable muffle units, positioned transversely of the leer and its annealing chamber, whereby the contents of the latter are subjected to the proper degree of heat from said muffle units and their 50 adjuncts.

It further consists of the novel construction 55 of a leer, provided with inlet and outlet

let flues coacting with the inlet and outlet openings of a plurality of removable muffle units positioned transversely of the leer and 55 its annealing chamber, the outer ends of said units being supported upon the walls of the leer, and the top of said units being covered with cork brick, so that any desired unit can be removed and replaced 60 at will at a minimum expense.

If further consists of a leer and muffle units of the character aforesaid, wherein the products of combustion or the heating medium may or may not pass through adjacent muffle units in opposite directions in order to maintain a substantially uniform heat throughout substantially the entire area of the annealing chamber.

It further consists of other novel features 70 of construction and advantage, all as will be hereafter set forth and pointed out in the claims.

For the purpose of illustrating my invention, I have shown in the accompanying 75 drawings forms thereof which are at present preferred by me, since they will give in practice satisfactory and reliable results, although it is to be understood that the various instrumentalities of which my invention 80 consists can be variously arranged and organized and that my invention is not limited to the precise arrangement and organization of these instrumentalities as herein shown and described.

Figure 1 represents a transverse vertical 85 sectional view of a muffle leer embodying my invention, the section being on line 1—1 Figure 2.

Figure 2 represents a longitudinal vertical 90 section on line 2—2 Figure 1.

Figure 3 represents on a reduced scale a perspective view partly broken away of a muffle unit in detached position, showing the internal construction, and the inlet and outlet openings thereof.

Figure 4 represents a longitudinal sectional detail of a modified arrangement of muffles and stay bolts.

Figure 5 represents a transverse section on 100 line 5—5 of Figure 4, of the construction represented in Figure 4, with the ends of the muffle open.

Figure 6 represents a section similar to

that of Figure 5, with the end of the muffle closed by an independent removable plate.

Figure 7 represents a fragmentary end section of a muffle and a flue extending up to 5 its top.

Similar numerals of reference indicate corresponding parts.

Referring to the drawings:

In carrying out my invention, which is 10 capable of adaptation to a leer of any standard or conventional type, I employ muffle or muffle units 1 composed of the top 2, bottom 3, ends 4, and sides 5, the same being constructed of sheet iron or the like and 15 the base or bottom 3 having in the opposite ends thereof the openings 6 and 7, which communicate respectively with the inlet flue 8 and outlet flue 9, as will be understood from Figure 1. If desired, of course, these 20 openings 6 and 7 may be either in the base or the bottom of the unit, or may be so placed as to be near the ends of the muffle. These muffles or muffle units are shown in the present instance as being rectangular, 25 but they may be obviously of other shapes and made of other material than sheet iron.

The top 2 and bottom 3 of each muffle is braced and reinforced by stay bolts 10, so that a rigid and durable structure is produced. If desired a plate of steel may be 30 placed on top of the muffle, to which the stay bolts may be attached, all these parts being in the outside air and not entirely covered by the insulating material. The muffles may 35 be of one standard dimension or construction and are supported at their outer ends on the furnace walls 11 and 12 and 13 and 14 in any suitable manner, as will be understood from Figure 1, the outer furnace walls 15 40 being preferably built up sufficiently high to enclose the muffle ends 4, while along the tops of the muffles, I place a layer of cork brick 16. The muffles are arranged in parallelism upon their supporting walls with 45 the openings 6 and 7 aligning with the coacting flues, it being understood that the gases can if desired travel in adjacent muffles in opposite directions, as will be understood from the arrows in Figure 2 and in order to 50 allow for the expansion and contraction of the muffle walls under the heat to which they are subjected, I arrange the juxtaposed walls slightly out of contact, so as to provide the spaces 17 as seen in Figure 2, which obviously 55 permit of the requisite expansion of the muffle walls. It will be seen from the foregoing that I have provided a series of detachable or removable muffles or muffle units which can be readily assembled in 60 position, each unit being independent of the other, so that in case of an explosion, or any damage to any of said muffles or units, it is only necessary to remove the cork brick 16 above it, take out the desired or injured 65 unit and replace it by a new one. This can

be done in a relatively short space of time and with a great saving of materials and labor, as compared with the present practice of tearing down or dismantling the portion of the leer, which may be damaged by an 70 explosion or from other causes. I have deemed it unnecessary to describe in detail the construction of the leer or annealing furnace, as my invention is applicable to any 75 standard or conventional leer, as is evident, the producer gas or other source of heat in the present instance being introduced at the point 18 and passing to the inlet flue 8 through the opening 19. 20 designates the annealing chamber containing the tray 80 21 for the ware or articles to be annealed which is located above the arch 22, and it is of course obvious that the articles to be annealed may be moved in and out of the furnace on cars or travelling aprons passing 85 through the furnace, as is customary, if desired.

Referring to Figures 4, 5 and 6, in which modified constructions are illustrated, 18' represents a top plate spreading across **T** 90 bars 19' resting upon a plurality of muffles which are separated at a distance from each other sufficient to admit between them pairs of tie bars 20' which are exposed to the atmosphere. 95

21' designates angle bars beneath the muffles 1 and extending beyond the latter so as to receive the lower ends of the bars 20'.

In Figures 5 and 6 the top plates 18' rest upon the **T** bars 19' and the material difference between the two constructions resides in the fact that the muffles in Figures 5 and 7 are open-ended and in Figure 6 closed by removable plates 22.

In the construction of Figure 7 the muffles have open ends and the flues extend up to 105 their tops.

Having thus described my invention what I claim as new and desire to secure by Letters Patent, is:—

1. The combination of a non-metal leer and a plurality of independent removable metallic units serving as muffles therefor and having openings in their opposite portions adapted to serve as either inlet or outlet openings and means for bracing said metal units. 115

2. The combination of a non-metal leer having inlet and outlet flues, and a plurality of independent removable metallic units serving as muffles therefor and having openings in their opposite portions coacting with said flues and adapted to serve as either inlet or outlet openings and means for bracing said metal units. 120

3. The combination of a non-metal leer having inlet and outlet flues, means to pass products of combustion through adjacent flues, a plurality of removable muffle metal units arranged transversely of said leer and 130

having openings at or near each end serving as either inlet or outlet openings and means for bracing said metal units.

4. The combination of a non-metal leer
 5 having inlet and outlet flues, means to pass products of combustion through adjacent flues, a plurality of removable muffle metal units arranged transversely of said leer and having openings at or near each end serving
 10 as either inlet or outlet openings, means for bracing said metal units and an annealing chamber located below and in proximity to said units.

5. The combination of a non-metal leer
 15 having upright inlet and outlet flues, a plurality of removable metal muffles arranged transversely of said leer and having openings at or near each end coacting with said flues and serving as either inlet or outlet
 20 openings, the top of said muffles being covered with insulating material and stay bolts for bracing said units.

6. The combination of a non-metal leer having upright inlet and outlet flues, a plurality of removable metal muffles arranged transversely of said leer and having openings at or near each end coacting with said flues and serving as either inlet or outlet openings, the outer ends of said muffles being suitably supported with reference to said flues, and the top of said muffles being covered with insulating material and stay bolts for bracing said units.

7. In a muffled leer, a removable metal muffle unit, composed of a top, sides, ends and bottom, said unit having openings at or near its opposite ends adapted to serve as either an inlet or outlet for the hot gases and means for bracing said unit.

- 40 8. In a muffled leer, a removable metal muffle unit, composed of a closed top, sides and ends, and a bottom having openings at

or near its opposite ends adapted to serve as either inlet or outlet openings for the hot gases and means for bracing said unit. 45

9. In a muffled leer, a removable muffle unit, composed of a top, sides, ends and bottom, stay bolts common to said top and bottom, and openings at or near the opposite portions of said unit adapted to serve as either inlet or outlet openings for the hot 50 gases.

10. In a muffled leer, a removable metal muffle unit, composed of a top, sides, ends and bottom, said unit having openings at or 55 near its opposite ends, and being adapted to serve as either an inlet or outlet for the hot gases, and inlet flues communicating with said openings, the upper ends of the walls of said flues supporting said units and means 60 for bracing said unit.

11. In a muffled leer, a plurality of metal muffles arranged side by side and out of contact, each being composed of a closed top, sides and ends, and a bottom having openings at or near its opposite ends adapted to serve as either inlet or outlet openings for the hot gases, and inlet and outlet flues communicating with said openings, the wall of 65 said flues supporting said muffles and stay 70 bolts for bracing said muffles.

12. In a muffled leer, a removable muffle unit, composed of a plurality of box-like units comprising a closed top, sides, ends and bottom, stay bolts common to said top 75 and bottom, and openings at or near the opposite portions of said unit adapted to serve as either inlet or outlet openings for the hot gases.
